UNITED STATES PATENT OFFICE.

DELFINO DE ROSA, OF CHISHOLM, MAINE.

GUARD DEVICE.

1,010,352.

Specification of Letters Patent. Patented Nov. 28, 1911.

Application filed July 20, 1910. Serial No. 572,832.

To all whom it may concern:

Be it known that I, DELFINO DE ROSA, a subject of the King of Italy, residing at Chisholm, in the county of Franklin and

5 State of Maine, have invented certain new and useful Improvements in Guard Devices, of which the following is a specification, reference being had to the accompanying drawings.

10 This invention has relation to an improved guard device for the cords or ropes of an automatic fire alarm system of that character shown and described in my pending application filed April 18, 1910, Serial 15 Number 556,105.

The object of the present invention resides in the provision of a simple and efficient guard which also acts as a support for the cords or wires which are extended over 20 the walls of the various apartments of a building so as to afford protection for the same and prevent them being cut by a knife or other sharp instrument in the hands of a malicious person and thus giving a false 25 alarm.

With the above and other objects in view, the invention consists of the novel features of construction, combination and arrangement of parts hereinafter fully described 30 and claimed, and illustrated in the accompanying drawings, in which—

Figure 1 is a fragmentary diagrammatic view of a portion of a building showing the application of my improved protecting 35 guard in a system of the above mentioned character; Fig. 2 is an enlarged detail transverse section illustrating the manner of attaching the guard to the wall; and Fig. 3 is an enlarged detail perspective view of the 40 device.

In my prior application a fire alarm system is shown embodying a plurality of alarm actuating devices and a system of cords or ropes extending through the various 45 rooms of the building whereby when any one of the cords is burned through by a flame originating in the room, the alarm is operated. It is for the purpose of protect-

ing these cords so that they will not be inadvertently or intentionally severed by other causes than fire, that my improved 50 guard device is provided.

The guard, as more clearly illustrated in Fig. 3 of the drawing comprises a continuous spirally coiled wire rod 5 which is 55 adapted to be secured to the wall W of the room adjacent to the floor, by means of the staples or other fastening devices 6 which engage upon the coils of the wires. Through this coiled wire guard the cord C which 60 controls the alarm operating devices extends and is movable. The coils of the wire guard are spaced a sufficient distance apart to admit a very small flame so that the alarm 65 will be sounded at the start of the fire. The guard also holds the cord in its proper position alongside of the walls of the apartment so that it cannot be accidentally pulled away from the same and broken. Upon the coils of the rod 5 a longitudinally extending 70 wire 7 is arranged. This wire may be of the same or heavier gage than the wire 5 and is soldered or otherwise secured thereto. It will be noted from reference to Fig. 2 that the wire 7 is disposed along the front edge 75 of the guard at its center thereby affording protection for the rope or cord which passes through the same while the bottom of the guard between the coils remains open so that the flames may readily pass between the 80 same and ignite the cord.

From the foregoing it will be seen that by means of my improved guard device the alarm controlling cords are properly protected against being severed by falling articles which might be accidentally dropped by the occupant of the apartment, while at the same time the operation of the alarm 85 system is in no manner affected.

The device is extremely simple and very 90 efficient in practical use. It may also be manufactured at a low cost and can be easily and quickly installed.

Having thus described the invention what is claimed is—

95 A guard of the character described com-

prising a spirally coiled wire rod rigidly secured at intervals to the wall of an apartment to provide an open housing, an alarm controlling cord in said housing, and a 5 single wire rod longitudinally disposed upon the exterior of the coils and diametrically opposite to the secured portions thereof to provide a protection for the cord housed

within the coils, substantially as and for the purpose specified.

In testimony whereof I hereunto affix my signature in the presence of two witnesses.

DELFINO DE ROSA.

Witnesses:

ISAAC B. CLARY,
ABBIE M. HORDING.
